GUN BARREL CLEANING DEVICE

Arthur C. Hopkins, Carthage, N. Y.

Application December 17, 1954, Serial No. 476,001

3 Claims. (Cl. 15—164.16)

The present invention relates to devices for cleaning the bores of guns, and particularly of guns which have helically rifled barrels.

It is important to properly clean the barrel of a gun after use. In cleaning a gun barrel, brushes, cloths, and swabs have been used, but none of these does a completely satisfactory cleaning job on a rifled gun barrel, because they do not properly wipe the sides and tops of the lands, with the result that burned powder and other foreign matter is not properly cleaned from the rifling.

One object of the present invention is to provide an improved cleaning device, suitable for cleaning either small or large bore gun barrels, and with which the gun tube or barrel can be quickly, thoroughly, and properly cleaned without danger of scratching or mutilating the rifling lands.

Another object of the invention is to provide a gun cleaning device in which the actual cleaning member is made of a material that is resilient in nature and that will be held by its own resiliency with a firm enough pressure against the sides and tops of the lands of the barrel to insure thorough and proper cleaning thereof, and removal completely therefrom of any traces of powder, or other foreign matter.

Another object of the invention is to provide a device of this kind which has a removable wiping member, which may readily and easily be removed and replaced, when it becomes dirty or worn.

Another object of the invention is to provide a device of the character described which is simple in structure, efficient in operation, and inexpensive to manufacture.

Other objects of the invention will be apparent hereinafter from the specification and from the recital of the appended claims.

In the drawing:

Fig. 1 is a part axial section, part side elevation of a gun cleaning device made according to one embodiment of this invention;

Fig. 2 is a view looking at one end of this device, but on a slightly reduced scale;

Fig. 3 is a part axial section, part side elevation of a removable cleaning member made according to a somewhat different embodiment of the invention;

Fig. 4 is an end view of this cleaning member;

Fig. 5 is a fragmentary transverse section on an enlarged scale, illustrating the action of the cleaning member of the present invention in cleaning a rifled gun barrel;

Fig. 6 is a side view showing a segment of a cleaning member made according to a still further embodiment of the invention;

Fig. 7 is a view looking at the tip of this cleaning segment;

Fig. 8 is an axial section of a cleaning head made according to still another embodiment of this invention for small bore guns; and

2

Fig. 9 is an end view of this cleaning head.

Referring first to the embodiment of the invention shown in Figs. 1 and 2, the gun cleaning device here shown comprises a ram rod 20 having a detachable head 21 threaded thereon. The head has a stem 24 which threads into a hole in one end of the ramrod. The head 21 is formed with a cylindrical, peripheral seating surface 22 and with a transverse shoulder 23 intersecting said surface.

10 In the embodiment of the invention shown in Fig. 1, there are mounted on the seating surface 22 three separate ring-shaped cleaning members 25. Each cleaning member comprises a hard paper or plastic core 26 in the form of a ring, and soft, yielding, resilient, pliable, compressible, flexible, absorbing material 27 which extends circumferentially about and is bonded to the core. This cleaning material may be a material such as wool felt, a felted fibrous material cut on the bias, a-braided material, or the like. The material used will be a material free of lint. In the embodiment of the invention shown in Figs. 1 and 2 the cleaning material on each of the cores 26 is in the form of a single piece of material shirred circumferentially. After it is shirred, the material is also preferably notched with circumferentially V-shaped notches, 25 as indicated at 28 in Fig. 1, and its edges are preferably beveled-off, as indicated at 29, so that adjoining rings will together form further V notches 30. The rings are held on the head 21 by a clamping disc or plate 32 which has a stem portion 33 that threads into a counterbore in head 21. The clamping disc 32 may be formed with four radial spokes shown at 35 in Fig. 2 for easy manipulation.

The V-grooves or notches 28 and the bevels 29 reduce the peripheral area of the cleaning material, providing a 35 soft pliable yielding surface which will depress and conform to all the surfaces within the gun tube.

The several rings 25 together are somewhat less in length than the length of the cylindrical surface 22, and are of somewhat greater diameter than this surface so 40 that they are free to float axially between shoulder 23 and clamping disc 32.

Instead of making the cleaning device with a plurality of separate rings, however, a single tubular cleaning 45 member may be provided, as illustrated in Figs. 3 and 4. This device is similar in construction to the cleaning rings shown in Fig. 1. It has a hard paper or plastic core 26' and soft, yielding, resilient, pliable, compressible, flexible, absorbing material 27', such as wool felt, free of lint, bonded to the core with a resilient bond. The material 50 27' is preferably shirred circumferentially, and again is preferably notched with V notches, as indicated at 28'. The ends of the material may also be beveled off as denoted at 29'. The tubular cleaning member of Figs. 3 and 4 may be mounted upon the same head 21 as the several ring cleaning members 27 of Fig. 1, and in the same way.

Instead of making the cleaning material in one piece and shirring it circumferentially, it may be made of a 60 plurality of identical individual segments, such as shown at 37 in Figs. 6 and 7. These segments are bonded to the hard paper or plastic core by resilient bonding material as with the previous embodiments of the invention. They are butted against one another and arranged in abutting relation circumferentially about the core. The segments 37 are again made of resilient, pliable, compressible, yielding, soft, flexible, absorbing material, such as wool felt free of lint, felted fibrous material cut on the bias, or braided material. Each of the segments is provided with a plurality of V notches, such as shown in 65 38, and beveled off at its edges as shown at 39. Pref-

erably the several notches of the several segments are aligned circumferentially of the core.

For small bore guns the cleaning head may comprise simply a plurality of rows of circumferentially shirred, resilient, soft, compressible, pliable, yielding, flexible, absorbing material, such as previously described, bonded to a single hard paper or plastic core 46, as shown in Figs. 8 and 9. In the embodiment of the invention shown in Figs. 8 and 9, there are four rings of shirred cleaning material bonded to a single core 46. Each ring is beveled off at its ends as denoted at 49, forming thereby with the adjacent ring of cleaning material a V notch 48. In this case, the core 46 may be directly threaded on the reduced diameter portion 51 of the ram rod 50.

In use the cleaning device is simply shoved back and forth axially in the bore of the gun which is to be cleaned. A rifled gun barrel is shown in Fig. 5 at 60. This gun barrel has lands 61 formed in a helix. The diameter of the soft, pliable cleaning material in its uncompressed condition is made slightly larger than the diameter of the bore of the gun tube 60 between the lands 61. As the cleaning device is moved back and forth axially in the gun, it is compressed slightly radially around its whole periphery because of this difference in diameters. Moreover, as the cleaning device is moved back and forth, the portions of the shirrs or segments 63, that engage opposite side of the lands, are compressed and bent aside by the sides 62 of the lands, while the portions of the shirrs or segments 64 of the material that engage with the tops of the lands, are simply compressed radially. The material, therefore, has intimate contact under pressure with the sides and tops of the lands of the barrel, and with the bottoms of the grooves between the lands. Furthermore, since the rifling is helical, different segments or gathers of the material are in engagement with the sides and tops of the lands of the gun barrel at different points along the length of the lands. At one point along its length, therefore, a segment or gather of material may be bent in one direction by contact with one side of a rifling land; at another point along its length this same segment or shirr may be compressed axially by the top of this same land; and at still another point along its length this same segment or shirr may be bent in the other direction by the opposite side of this same land. This enhances and improves the intimacy of contact between the cleaning material and the lands both on the sides and tops of the lands along the full length of the rifling as the cleaning device is reciprocated back and forth manually in the barrel. The V-grooves or notches in the material and the beveled ends of the material increase the pliability of the material so that the soft, pliable material will, as previously stated, depress and conform to all the surfaces within the gun barrel, wiping them clean.

In the embodiment of the invention shown in Fig. 1, the cleaning members 25 are free to move axially and to rotate as the cleaning device is reciprocated back and forth in the gun barrel. This also improves the wiping, cleaning action. These same additional movements can be achieved with the embodiment of the invention shown in Figs. 3 and 4 by making the length of the core 26' less than the length of cylindrical surface 22 and by making the diameter of this core greater than that of this surface.

When a device such as described is employed in cleaning the gun barrel, therefore, there will be thorough, proper cleaning. The device is simple in structure, and

inexpensive to make. As it becomes dirty or worn, the cleaning member may be removed from the head 21 by first removing the clamping disc 32, in the case of the cleaning device shown in Figs. 1 to 4 inclusive, or in the case of the small bore cleaner of Figs. 8 and 9, the core can be just threaded off the ramrod. The dirty, worn cleaner can be thrown away, and replaced by a new cleaner.

Instead of using a ram rod 50, such as shown in Fig. 8, a cord may be used to pull the cleaning material through the gun barrel, particularly in the case of a small bore gun. The core can then be glued or otherwise suitably fastened to the cord.

While the invention has been described in connection with several different embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains, and as may be applied to the essential features hereinbefore set forth, and as fall within the scope of the invention or the limits of the appended claims.

Having thus described my invention, what I claim is:

1. A cleaner for gun barrels comprising a manipulable holder, a hard, ring-shaped core mounted on said holder, and soft, yielding material shirred circumferentially about and bonded to said core, the shirrs in said material providing a plurality of individual gathers, each of which is adapted to be bent and depressed in a plurality of directions when the cleaner is reciprocated in a gun barrel.

2. A cleaner for gun barrels comprising a rigid holder, a hard, ring-shaped core mounted on and surrounding a portion of said holder, and soft, yielding material shirred circumferentially about and bonded to said core, the shirrs in said material providing a plurality of individual gathers, each of which is adapted to be bent and depressed in a plurality of directions when the cleaner is reciprocated in a gun barrel, the internal diameter of said core being greater than the diameter of said portion of said holder and the length of said core being less than the length of said portion, whereby said core may rotate and move axially on said holder as the cleaner is reciprocated in a rifled gun barrel, and means for limiting axial movement of said core on said portion.

3. A cleaner for gun barrels comprising a manipulable holder, a hard, ring-shaped core mounted on said holder for axial and rotatable movement relative thereto, and soft, yielding material shirred circumferentially about and bonded to said core, said material being provided with a plurality of axially-spaced circumferentially extending grooves.
